UNITED STATES PATENT OFFICE.

WILLOUGHBY P. ELAM AND WILBUR F. BOGGS, OF PETERSBURG, ILL.; SAID BOGGS ASSIGNOR OF ONE-THIRD TO ELIJAH L. GALT, OF SAME PLACE.

GRAIN-DRILL.

SPECIFICATION forming part of Letters Patent No. 268,361, dated November 28, 1882.

Application filed June 1, 1881. (No model.)

To all whom it may concern:

Be it known that we, WILLOUGHBY P. ELAM and WILBUR F. BOGGS, citizens of the United States, residing at Petersburg, in the county of Menard and State of Illinois, have invented certain new and useful Improvements in Grain-Drills; and we do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 Our invention relates to a grain-drill; and the novelty consists in the construction and arrangement of parts for the general improvement of the device and its better adaptation to the required service, as will be more fully 20 hereinafter set forth, and specifically pointed out in the claims.

The invention is designed as an improvement upon the device patented to us January 25, 1881, and numbered 237,001.

25 The invention is fully illustrated in the accompanying drawings, which form a part of this specification, and in which—

Figure 1 is a top plan view. Fig. 2 is a vertical section, and Figs. 3, 4, and 5 details.

30 Referring to the drawings, A represents the main frame of a sulky grain-drill, having journals a for the riding-wheels, one of which carries a gear which is properly connected to a pinion upon the feed-bar, substantially as shown in the patent granted to us and hereinbefore mentioned.

Upon the front bar, a', of the frame A is secured brackets e, in which are pivoted the forward ends of curved drag-bars C, bifurcated 40 at e' to receive the foot and leg of the planting-shoe D. The frame C is held as against lateral play by tie-rods c', as shown, and a vertical rod, C', surrounded by a spiral spring, C', which bears upon the upper surface of each drag-bar C, and under an arm, E, through which each rod C' passes, a headed end allowing the said rods to pass upward as the shoe overrides obstructions, while the springs exert a constant force to hold the shoes in action. 45 The bar E operates loosely in sockets e', formed

in the free ends of arms which are rigidly secured to or upon the axle B.

Secured upon the axle B is a sleeve, f, carrying a toothed segment, F, in which operates a spring-pawl, f', upon a trigger-lever, F', loosely hung upon the shaft B. 55

A pedal-lever, G, which also serves as a pivotal bolt for one or more of the drag-bars, is connected by a spring-pawl, g, to the segment F. By releasing the pawl g from the segment and employing the lever F' the drag-bars and connected shoe or drill may be lifted out of operation, and this action, through an inclined lug, x, rigid upon the axle B, operating upon a transverse spring sliding bar, H, throws the 60 arm I or equivalent device outward, and thus automatically throws the operating-gear out of mesh.

J represents an arm having perforations j, which connects by a link, j', with an arm, K, 70 rigid upon a bar, K', journaled in the frame A at k, and having rigid arms L, in the sockets l of which loosely operates a perforated bar, M. Through these perforations operate the vertical rods N, which are bifurcated below to receive the axis of the rollers or coverers O, loosely secured by frames P to the rear portions of the drag-bars. By this construction the link J' may be adjusted at will in the perforations J, and the coverers have a vertical 75 play independent of the drag bars or drills, a spring, Q, acting to allow the play and to exert a constant force to hold the coverers in operation.

It will be observed that while there is vertical play between the planting and covering devices independent of each other, yet they may both be elevated out of operation by the same lever, F'. 85

R represents the feed bar or shaft carrying 90 the feeding-wheels S, having seed-cells s, and an extended periphery upon each side of the cells, as seen at s' in the enlarged view, Fig. 5. By this construction the seed will not be crushed or broken by the cell-partitions. 95

What we claim as new is—

1. The drag-bars C and shoes D, the pivoted rod C', spring C, and elevating means, combined with the covering-wheels O, pivoted to the rear ends of the drag-bars, and means for 100

throwing them in and out of operation at will, as specified.

2. The drag-bars C and shoes D, the pivoted rod C', spring C², and elevating means, combined with the covering-wheels O, pivoted to the rear ends of the drag-bars, the pivoted rod and spring N Q, and means for throwing them in and out of operation at will, as specified.

3. The axle B, segment F, lever F', and independently pivoted drilling and planting mechanism, combined with means, H I x, for automatically throwing the operating-gear out of mesh as the planting devices are forced out of operation, as and for the purpose set forth.

4. The combination of the pedal-lever G g, 15 drag-bars C, axle B, segment F, lever F', and drilling devices with the lug and bar H, shaft I, the pivoted spring covering devices O P Q, link j, adjusting-arm J, and feeding mechanism, as and for the purposes set forth. 20

In testimony whereof we affix our signatures in presence of two witnesses.

WILLOUGHBY P. ELAM.

WILBUR F. BOGGS.
